REGINALD W. BECKETT AND OTTO THIEL, OF DETROIT, MICHIGAN, ASSIGNEES, BY
MESNE ASSIGNMENTS, TO TIMKEN SILENT AUTOMATIC COMPANY, OF DETROIT,
MICHIGAN, A CORPORATION OF MICHIGAN

CENTRIFUGAL SPRAY DEVICE

Application filed June 18, 1930. Serial No. 462,062.

The present invention relates to centrifugal sprayers or atomizers and more especially to oil sprayers for rotary liquid fuel burners.

Various forms of centrifugal sprayers have been used for finely dividing liquid fuel for burners, and among others a rotary cup to which the oil is delivered by means of tubes mounted in the bottom and projecting down into an oil reservoir, the lower end being fastened to scoop up the oil as the cup rotates. Due to the inertia of the oil, this scooping results in the oil flowing up the tube and into the cup through the upper open end of the tube. In the particular structure referred to, the cup is also provided with openings in its bottom to permit air to enter the cup.

Various objections were encountered in this old structure and not the least of these was the admission of air to the cup. This practice resulted in a combustible mixture being produced in the cup with the resulting liability to combustion therein. When, however, the holes in the cup were closed, difficulty was met in providing through the air admission openings sufficient air admission for complete combustion of the oil capable of being sprayed by a given cup.

Further, it was found that when using two tubes, which number is ample for the largest size burner, more than half of the cup was without function in spraying. Among the objects of the present invention, therefore, is a sprayer structure that overcomes the objections above indicated and eliminates useless material and at the same time provides for sufficient air admission to provide for complete combustion of all of the oil capable of being sprayed by the device.

Another object is a novel construction of sprayer in which is admitted along with the oil only that insignificant amount of air entrained through the tubes.

Another object is a combined sprayer and air impeller which, in the smaller installations, supplies sufficient combustion supporting air without the necessity of using additional air impelling means.

Still other objects will readily occur to those skilled in the art upon reference to

the following description and the accompanying drawing in which Fig. 1 is a top plan view of the device embodying the invention, Fig. 2 is a vertical section on the line ABCDE of Fig. 1, Fig. 3 is an elevation of one of the scoop tubes and fixing means, and Fig. 4 is a top plan view of such a tube and its fixing means.

Referring to the drawing, the spray device is indicated as comprising a central sleeve member 10 whose lower end is enlarged to form a downwardly opening cup or oil splash shield 11 providing against oil being splashed out of the reservoir (not shown). The upper portion of member 10 is machined to cylindrical form as at 12 and may have a reduced cylindrical portion 13 for securing thereon an air impeller (not shown).

Mounted substantially vertically in the horizontal upper wall 15 of the cup 11 are a plurality of oil scooping tubes 16, each provided at its lower end with a pick finger 17 adapted to dip into the oil in the reservoir and scoop up some of the oil as the spray device is rotated. These tubes, as indicated in the drawing, are preferably rolled from a flat blank and provided with an integral ear 18 formed to receive a screw 19 by means of which the tubes may be fixed in the wall 15 against rotation and against longitudinal movement. The upper end of each tube also is provided with a finger or spacing lug 9, the purpose of which will be described later.

Mounted upon the cylindrical portion 12 of member 10, above the cup 11 is the spray device proper, designated as a whole by the numeral 20. This consists of a central sleeve 21, fitting snugly upon the portion 12, and carrying a chambered member formed of a lower dished and formed sheet metal member 22 and an upper dished and formed sheet member 23.

As shown, the lower member 22 is dished to a greater degree than the upper member 23, so that a central chamber 24 having parallel side portions 30 is formed when the two are put together. As indicated in Fig. 1, a top plan view of these members shows them to have fan-shaped end portions 25 whose

ends terminate in arcs described about the axis of the spray device.

As indicated in Fig. 2, the fan-shaped portions 25 extend upwardly and outwardly 5 from the chambered portions 24 of the spray device 20 in a smooth curve.

The member 22 is provided in its mid-horizontal portion with openings for admitting tubes 16 and is also provided with formed up 10 side walls 30 for the chambers 24, these walls terminating at their upper edges in flange portions 31 bent over the edges of member 23 and serving to secure the two members 22 and 23 together at these points. Along the 15 side edges of the fan-shaped portions 25, the two members are both provided with wide up turned flanges 32 parallel and adjacent, when the parts are assembled, and secured together by any suitable means, as by welding. These 20 flanges 32 are of such width that they extend above the upper face of member 23 for a short distance as shown clearly in Fig. 2.

In assembling members 21, 22 and 23, the latter two will be spaced at the fan-shaped 25 portions 25 only a short distance, to provide a nozzle opening 33, of the fan width but of small height, and both are pressed tightly on and preferably welded to the sleeve 21. It is also preferred to insert at each side of 30 sleeve 21 a spacer and divider 34, which fix the depth of and separate the chambers 24.

As shown best in Fig. 2, the spray device 20 is fixed in adjusted position on member 10 by means of two set screws 40 passing through the side walls 30 and sleeve 21 and contacting with member 10.

In the form of burner for which the present device is especially suitable, it is often necessary, when making an installation, to raise or 40 lower the oil spray, and it is for this reason the device 20 is so arranged as to be movable on the member 10. However, in order that it may not be lowered so much as to interfere with the flow of oil from the top of tubes 16, 45 these are provided with the spacer lugs or fingers 9 which prevent the closing of the tubes by striking the member 23.

In the operation of the device the sprayer is mounted upon the shaft of a suitable motor, which shaft passes up into and is fixed in the central opening 45 of the member 10 and an annular oil reservoir provided for the actuation of the scoop tubes 16.

Rotation of the sprayer causes the scoops 50 to pick up oil from the reservoir and causes such oil to flow up tubes 16 and be discharged into chambers 24 against the inner wall of member 22. On account of the rapid rotation of the device and the inertia of the oil, the 55 latter will spread out fan wise and there will result a wide thin stream of oil substantially the width of opening 33, the tubes 16 being so placed that the edge of the fan of oil coincides with the outer arc-shaped edges of the sprayer.

Further, the flanges 32 act as impeller blades and cause flow of air in considerable quantity while the substantially two-thirds cut away portion of the device allow admission of such air. In fact, in burners intended to operate at only a small part of their capacity, it has been found that no additional air supply devices are necessary. The blades 32 tend to cause outward movement of the gases with which they are in contact when the device is rapidly rotated. Such outward movement, of course, causes a lowering of pressure near the center line and such lowering of pressure causes the flow of gases into this low pressure region. It so happens that the present device is not exposed to the combustion chamber but it is covered by means of a fan element and therefore combustion gases do not have access to the low pressure region. This fan device is not shown, as it forms no part of the present invention which is limited to the device shown in the drawing. A patent which is below identified, shows the fan device as being also the cover for the oil cup but in the present instance, the cover for the oil chambers is integral with the chambered element and therefore the fan device will be above and prevent access of the combustion gases.

It should be noted that the present invention provides a spray device in which the spray discharge fan-shaped nozzle portions and their corresponding chambered portions form in effect merely continuations of the scoop tubes and that little, if any, air can get into chambers 24, thereby reducing to a large extent, if not eliminating, the formation of a combustible mixture in the chambers and the consequent danger of combustion therein.

A form of oil burner to which the present device is particularly well adapted is shown in the patent to Forest A. Heath, No. 1,707,474, issued April 2, 1929.

Now having described the invention and the preferred form of embodiment thereof, it is to be understood that said invention is to be limited, not to the specific devices herein set forth, but only by the scope of the claims which follow:

We claim:

1. A centrifugal spray device comprising a member containing a pair of substantially fan shaped chambers, the outer ends of which are open and in a different plane from the inner ends and means for supplying spray liquid to said chambers.

2. A centrifugal spray device comprising a member containing a pair of substantially fan shaped chambers, the outer ends of which are open and in a plane above the plane of the inner ends and means for supplying spray liquid to said chambers.

3. A centrifugal spray device comprising a member containing a pair of substantially

fan shaped chambers formed from upper and lower bowed or dished plates, the lower plate being bowed or dished more than the upper, and also provided with side flanges, 5 whereby to provide a chambered portion centrally of said device and means for supplying spray liquid to said chambers.

4. A centrifugal spray device comprising a member containing a pair of substantially 10 fan shaped chambers formed from upper and lower bowed or dished plates, the lower plate being bowed or dished more than the upper, and also provided with side flanges, whereby to provide a chambered portion centrally of 15 said device, said plates being also spaced apart a short distance at their ends to provide a relatively wide opening of small height and means for supplying spray liquid to said chambers.

20 5. A centrifugal spray device comprising a member containing a pair of substantially fan shaped chambers formed from upper and lower plates having means for fixing them together, said plates being also provided with 25 upstanding flanges along their side edge portions adapted to act as fan blades and means for supplying spray liquid to said chambers.

6. A centrifugal spray device comprising a member containing a pair of substantially 30 fan shaped chambers each provided with an outlet at its arc shaped end, an inlet tube for each chamber extending thereinto near the center point, a downwardly extending hub member for said device and means for fixing 35 said tubes in said hub member.

7. A centrifugal spray device comprising a member containing a pair of substantially fan shaped chambers each provided with an 40 outlet at its arc shaped end, an inlet tube for each chamber extending thereinto near the center point, a hub member upon which said chambered member is adapted to be adjustably mounted, means for fixing said tubes in 45 said hub member and means for preventing the closing of the upper end of said tubes at any adjusted position of the two members.

8. A centrifugal spray device comprising a member containing a pair of substantially fan shaped chambers each provided with an 50 outlet at its arc shaped end, an inlet tube for each chamber extending thereinto near the center point, a hub member upon which said chambered member is adapted to be adjustably mounted, means for fixing said tubes 55 in said hub member so as to prevent longitudinal and rotative movement, and means for preventing the closing of the upper end of said tubes at any adjusted position of the two members.

60 REGINALD W. BECKETT.
OTTO THIEL.
